UNITED STATES PATENT OFFICE.

ROBERT W. COX AND JOHN H. ONTRICH, OF WASHINGTON, DISTRICT OF COLUMBIA.

POCKET CHECK-PUNCH.

No. 854,630.

Specification of Letters Patent.

Patented May 21, 1907.

Application filed February 9, 1907. Serial No. 356,589.

To all whom it may concern:

Be it known that we, ROBERT W. COX and JOHN H. ONTRICH, citizens of the United States, residing in Washington, District of Columbia, have invented a new and useful Improvement in Pocket Check-Punches, of which the following is a specification.

This invention relates generally to check punches or perforators, and more particularly to one so constructed as to be conveniently carried in the pocket.

The object of the invention is to provide an exceedingly simple and efficient form of pocket check punch, which will not only be useful as a check punch, but can also be utilized as an advertising medium.

With these objects in view, the invention consists essentially of two metallic disks connected together by means of a rivet, the upper disk being adapted to turn upon the lower disk, said upper disk being constructed with means for perforating a check held between the said disk, the lower disk having a perforated bed portion upon which the check is perforated, said lower disk being also provided with means for maintaining the upper disk in its proper position with relation to the lower disk, and also with means for holding the said upper disk steady after it has once been properly adjusted.

The invention consists also in various features of construction and also in the novel manner of combining and utilizing said features, all of which will be fully described hereinafter and pointed out in the claims.

In the drawing forming a part of this specification:—Figure 1 is a perspective view of a pocket check punch constructed in accordance with our invention. Fig. 2 is a top plan view of the same. Fig. 3 is a sectional view on the lines 3—3 of Fig. 2. Fig. 4 is a plan view of the bottom disk and Fig. 5 is an inverted plan view of the upper disk. Fig. 6 is a detail perspective view showing the perforated bed-plate and fulcrum lip.

In constructing a pocket check punch in accordance with our invention we employ a metal disk A which may be of any suitable material and this is the disk which we designate the lower disk. At diametrically opposite points this disk is provided with slight extensions, the ends of which are curved as

shown at A', in order to afford a convenient grip upon the device, it being understood that the said device is held between the thumb and fore-finger of one hand, while the upper disk is being adjusted with the other hand. The bottom disk A has a central opening A², through which passes the pivot post B, said central opening being preferably square in shape, so that when the parts are connected, the pivot or post B become rigid with the bottom disk A, and turning upon this central post or pivot B is the top or upper disk C, the upper end of the post or rivet being headed down to firmly connect all of the parts together. The upper disk C carries the numerals \$, and any other characters desired, said characters being preferably stamped or punched into the said upper disk in such a manner as to form punching dies which protrude from the lower face of said upper disk, as most clearly shown at C', in Figs. 3 and 5.

It will of course be understood that the check to be punched is held between the disks, and the upper disk adjusted so as to bring the proper numeral over the proper place on the check, and then by bringing that portion of the upper disk down upon the check, the proper numeral is punched into or upon the check, and to render this operation complete we provide a perforated bed-plate D which is punched up from the bottom disk as most clearly shown in Figs. 3, 4 and 6, the perforations of said portions being so arranged as to register with the protruding portions of the dies C' so as to render a complete perforation of the check possible. It will be understood, however, that it is not absolutely necessary for the bed-portion to be perforated, as it will be sufficient if the upper surface thereof is roughened. The bottom disk A has two transverse lips E and F punched therefrom and turned up at a right angle as shown in Figs. 3 and 6, said lips serving to hold the upper disk C the proper distance away from the lower disk A, and these lips also serve as a fulcrum when the check is to be perforated, the disk F being arranged between the center of the plate and the bed-portion D, and furthermore it will be noted that this lip F is provided with two teeth F' which are so spaced that they will

engage the radial grooves F^2 , produced in the lower face of the upper disk, so that when a numeral or other character is brought directly over the bed-plate D of the lower disk, 5 the teeth F' will enter the radial grooves F^2 and thereby hold the said upper disk against further pivotal movement, and the check can be then inserted and the edge of the disk pressed down, so as to punch the check. The 10 lip F also serves as a stop against which the edge of the check can be made to rest.

In order to provide for a perfect impression, we construct the outer or circumferential portion of the upper disk C upon a 15 slight inclination as shown at C^2 , so that when the disk is pressed down at one point for the purpose of punching the check, the portions so pressed down will come into parallel relation with the upper face of the bed- 20 portion D just as the check is to be punched, and in this manner a complete and perfect perforation or impression is obtained it being understood that the upper disk is made of metal sufficiently elastic or yielding to permit such movement, and then return to its 25 normal position, the moment the pressure is removed. The outer edge of the upper disk is milled to facilitate the adjustment of said disk.

30 The operation of the device will be thoroughly understood from the description already given, and it will be understood that if desired the advertisement of a bank or other financial institution may be stamped or 35 otherwise arranged upon either one of the disks at the time it is manufactured. It will also be understood that slight changes or variations in the details of construction may be had so long as the essential features of the 40 invention are not departed from.

Having thus fully described our invention,

what we claim as new and desire to secure by Letters Patent is:—

1. A check punch comprising a lower disk having a bed portion and a fulcrum adjacent thereto, and an upper disk carrying punching dies, said upper disk being rotatable upon the lower disk and adapted to have one edge pressed down into contact with the bed portion of the lower disk. 45

2. A check punch comprising a lower disk having a fulcrum and a roughened surface adjacent thereto, an upper disk rotatable upon the lower disk, and having its circumferential portion inclined, said inclined portion being provided with punching dies. 50

3. A check punch comprising the upper and lower disks pivotally connected, the lower disk having a lip punched therefrom, said lip being provided with teeth, the upper 60 disk having its central portion radially grooved, the teeth of the lip being adapted to engage the radial slots for the purpose of holding the upper disk, said upper and lower disks being provided with means for punching the check, as set-forth. 65

4. A check punch comprising the upper and lower disks pivotally connected, the lower disk having a bed portion punched therefrom and also two transverse lips, one 70 of said lips being provided with teeth, the upper disk having its central portion radially grooved and its circumferential portion inclined, said circumferential portion carrying the dies, all of said parts being constructed, 75 arranged and adapted to operate substantially as shown and described.
